UNITED STATES PATENT OFFICE.

JEROME W. WETMORE, OF ERIE, PENNSYLVANIA.

VEHICLE-SPRING.

SPECIFICATION forming part of Letters Patent No. 399,955, dated March 19, 1889.

Application filed April 2, 1888. Serial No. 269,224. (No model.)

To all whom it may concern:

Be it known that I, JEROME W. WETMORE, a citizen of the United States, residing at Erie, in the county of Erie and State of Pennsylvania, have invented a new and useful Improvement in Vehicle-Springs, of which the following is a specification.

My invention relates to spiral torsion-springs when applied to semi-elliptical springs of vehicles.

The objects of my improvement are to more completely combine the advantages of the conical coil, the cylindrical coil, and the torsion-springs in their application to semi-elliptical springs of carriages. I attain these objects by the construction illustrated in the accompanying drawings, in which—

Figure 1 is a front view of the spring applied to a semi-elliptical spring as a base; Fig. 2, a vertical view of the spring on its base, the body of the vehicle being removed; Fig. 3, the same view with a modification of the form of the spring, giving it greater flexibility by means of the additional arm and curve. In both the down-pressure is balanced evenly on each side of the base. This is substantially the same in all the applications of the spring. Fig. 4 is a vertical view when the body of the vehicle is not over the

axle; Fig. 5, a front view of Fig. 4; Fig. 6, a view of Figs. 4 and 5 from the side of the vehicle.

The springs may be of round steel and the ends flattened where attached to the semi-elliptical spring. The ends attached to the body would then be turned, as in Fig. 4, and held by clips.

The upper leaf of the half-elliptical spring will have greater distances from its ends to the ends of the leaf below it than in the elliptical spring, because of the increased contact with c , c' , and c^2 as the springs are depressed by the load.

What I claim is—

1. The oblong spiral spring, in combination with the body of the vehicle and the semi-elliptical base, substantially as described.

2. The combination of the spiral spring of irregular shape with the semi-elliptical spring and the body of the vehicle, substantially as described.

In testimony whereof I affix my signature in presence of two witnesses.

JEROME W. WETMORE.
